UNITED STATES PATENT OFFICE.

CLARENCE A. STRACHOTA, OF MINNEAPOLIS, MINNESOTA, ASSIGNOR TO LIPTAK FIRE
BRICK ARCH CO., OF MINNEAPOLIS, MINNESOTA, A CORPORATION OF MINNESOTA.

FIRE ARCH WITH AIR-INTAKE PORTS.

Application filed February 3, 1923. Serial No. 616,714.

My invention relates to furnaces such as used in connection with boilers and which include fire arches made up of blocks or tiles suspended from overhead beams; and the invention provides a highly efficient scheme for the introduction of air into the furnace through air intake passages provided in the fire arch.

Generally stated, the invention consists of the novel construction, arrangement and combinations of parts hereinafter described and defined in the claims.

In the accompanying drawings, which illustrate the invention, like characters indicate like parts throughout the several views.

Referring to the drawings:

Fig. 1 is a perspective showing a portion of a furnace and a portion of a fire arch, the latter having my invention incorporated therein;

Fig. 2 is a diagrammatic plan view illustrating the arrangement of air intake valves on the top of the furnace arch;

Fig. 3 is a transverse vertical section on the line 3—3 of Fig. 1, some parts being broken away;

Fig. 4 is a longitudinal section on the line 4—4 of Fig. 3, some parts being broken away;

Fig. 5 is a perspective showing one of the upper port-equipped blocks of the arch;

Fig. 6 is a view corresponding to Fig. 4, but illustrating a slightly modified arrangement;

Fig. 7 is a view corresponding to Fig. 5, but illustrating a slightly modified form of the port-equipped block;

Fig. 8 is a fragmentary vertical longitudinal section of the furnace and arch, illustrating a modified arrangement;

Fig. 9 is a view corresponding to Fig. 3, but illustrating a still further modified arrangement;

Fig. 10 is a vertical section taken from front to rear through the inner end of the fire arch, showing also a portion of an apron wall, and illustrating an arrangement of air intake ports for the introduction of air into the furnace through the upwardly curved inner end of the arch; and

Fig. 11 is a fragmentary section taken from front toward the rear through the fur-

nace arch and through an ignition arch and curtain wall extending from the ignition arch to the roof or main arch.

Referring first to the construction illustrated in Figs. 1 to 5, inclusive, the numeral 14 indicates the furnace wall in which are supported transverse main arch-supporting beams 15 in the usual or any suitable arrangement. From these main beams 15 laterally spaced arch beams 16 are supported by hanger brackets 17. The arch beams 16 support a double suspension arch made up chiefly of slidably interlocked upper arch blocks 18 and lower arch blocks 19, but also including rounded end blocks 20. The arch here illustrated may be assumed to be what is well known to the trade as the "Liptak double suspension arch". In an arch of this type, the upper blocks 18 have flanges that slide upon the flanges of the beams 16 and the lower or underfacing blocks 19 have reduced necks with flanges that slide upon lower flanges of the upper arch blocks. However, my invention is not limited to this particular type of arch nor to the particular way of suspending the arch-forming blocks. The first illustration of the invention is in connection with this type of arch and is preferably carried out as follows:

Certain of the upper blocks 18 are formed with large vertical ports or air passages 21 that open into or through a horizontal channel 22 that is formed between the lower portions of the upper blocks 18 and the upper portions of the lower blocks 19. Certain of the lower blocks 19 are also provided with air ports and passages 23 which may be located in vertical alignment with the ports 21, as best shown in Fig. 4, or may be offset longitudinally, as shown in Fig. 6. In any event, the ports 23, which deliver the air directly into the top of the furnace, are distributed over the surface of the arch so as to give a uniform accelerated combustion by the introduction of hot air into the furnace through said ports.

It will be desirable to vary the amount of air that will be drawn into the furnace through these air intake ports and this may be readily accomplished by the use of slide valves or gates 24, (see particularly Figs. 2, 3, 4 and 5), mounted to slide in grooves

in the tops of the upper blocks which have the grooves 21. As shown, these valves move under retaining bars 25 bolted to said blocks, (see particularly Fig. 5). One transverse row of valves 24 is connected by short links 26 and the other row by long links 27, to crank arms 28 of rock shafts 29 mounted in suitable fixed bearings 30. The valves 24 just described are in the form of cast metal plates, while the valve 31 shown in Fig. 7 is a refractory block having a cast lug bracket 32 secured thereon and to which the adjusting link may be pivoted.

Figs. 8 and 9 are sort of diagrammatic sections in which the blocks of the main fire arch are not individually shown and in which, furthermore, such arch might be of monolithic construction but formed with a longitudinal air channel 33 and with offset upper and lower air intake ports 34 and 35. In the arrangement illustrated in Fig. 8, the air channel 33 is connected to the delivery end of an air supply pipe 36 that may be assumed to lead from a fan or blower, not shown. Also in this arrangement, Fig. 8, the ports 34 are arranged to be opened and closed by valves 37 that correspond to the valves 24 previously described.

In the construction illustrated in Fig. 9, the ports 34 are connected to branch air pipes 38 that lead from a main air supply pipe 39, which, in turn, will be assumed to lead from a fan or blower, not shown. The branch pipes 38 are shown as provided with dampers 40, by means of which they may be opened more or less so as to distribute the air properly to the several ports. With the arrangements illustrated in Figs. 8 and 9, air will be fed into the furnace under pressure through the fire arch and will insure more complete combustion of the smoke. Also with the arrangements previously described, the additional supply of air through the fire arch will insure complete combustion. Obviously, the fire arch will be at high temperature, so that the air drawn in or forced in through the same will be pre-heated and delivered to the flames under high temperature, which is necessary to insure the desired complete combustion and abatement of the smoke nuisance, as well as economy in the use of fuel.

In Fig. 10, the main fire arch is shown as provided with an upwardly curved inner portion made up of wedge-shaped upper and lower blocks 18^a and 19^a, which, except for the wedge shape noted, are of the same form and arrangement as the blocks 18 and 19, the inner ends of the arch beams being upwardly curved to properly support the said upper blocks 18^a. The numeral 41 indicates an apron wall supported above the upturned end of the main arch but which constitutes no part of the present invention and, hence, may not be further considered. It should,

however, be noted that in this arrangement the air channel 22 between the upper and lower blocks has an upwardly curved extension 22^a that leads to ports 42 formed in or by the omission of certain of the blocks 19^a. In said arrangement, Fig. 10, certain of the upper blocks 18 are provided with the upper ports 21 and are equipped with valves 24, as in the construction illustrated in Figs. 1 to 5, inclusive.

In the construction illustrated in Fig. 11, an enlarged ignition arch 43 is supported below the outer end of the main arch by brackets 44 hung from beams 45, and a curtain wall 46 is supported by said brackets and extends from the ignition arch to the main arch. This construction need not here be further considered, except to note that certain of the blocks of the curtain wall 46 are formed with air intake ports 47 that are connected to an air trunk 48 in which is maintained air under pressure through a supply pipe 49 that leads from a fan or blower. Also, the air trunk 48 is shown as provided with auxiliary air intake ports 50.

What I claim is:

1. A double suspension arch comprising supporting beams, upper and lower arch-forming blocks hung therefrom with a longitudinal air passage between the said upper and lower blocks, said upper and lower blocks having air intake ports in communication with said longitudinal air passage.

2. A double suspension arch comprising supporting beams, upper and lower arch-forming blocks hung therefrom with a longitudinal air passage between the said upper and lower blocks, said upper and lower blocks having air intake ports in communication with said longitudinal air passage, the air ports in said upper and lower blocks being horizontally offset.

3. A double suspension arch comprising supporting beams, upper and lower arch-forming blocks hung therefrom with a longitudinal air passage between the said upper and lower blocks, said upper and lower blocks having air intake ports in communication with said longitudinal air passage, the said arch having an inwardly and upwardly extended portion and certain of the ports of said lower blocks being located in the said upwardly and inwardly extended portions.

4. A double suspension arch comprising supporting beams, upper and lower arch-forming blocks hung therefrom with a longitudinal air passage between the said upper and lower blocks, said upper and lower blocks having air intake ports in communication with said longitudinal air passage, and valves cooperating with the ports of the upper blocks.

5. A double suspension arch comprising supporting beams, upper and lower arch-

forming blocks hung therefrom with a longitudinal air passage between the said upper and lower blocks, said upper and lower blocks having air intake ports in communication with said longitudinal air passage, the said arch having an inwardly and upwardly extended portion and certain of the ports of said lower blocks being located in the said upwardly and inwardly extended portions, and valves cooperating with the 10 ports of the upper blocks.

In testimony whereof I affix my signature.

CLARENCE A. STRACHOTA.
